UNITED STATES PATENT OFFICE.

PETER LEE FERGUSON AND JOSEPH W. WHEELWRIGHT, OF OGDEN, UTAH.

SIGN.

1,170,441.

Specification of Letters Patent.

Patented Feb. 1, 1916.

Application filed July 8, 1913. Serial No. 777,909.

To all whom it may concern:

Be it known that we, PETER LEE FERGUSON and JOSEPH W. WHEELWRIGHT, citizens of the United States, residing at Ogden, in the county of Weber and State of Utah, have invented new and useful Improvements in Signs, of which the following is a specification.

This invention relates to signs and more particularly to illuminated signs.

One of the principal objects of the invention is to provide a sign particularly adapted for exhibiting automobile numbers and like indicia, which will be constructed in a simple and efficient manner and which will be cheap to manufacture.

A further object of the invention is the provision of a device of this character whose casing is constructed in such a manner that a light may be placed at one end and its rays reflected through each stencil equally irrespective of the distance from the light.

Further objects of this invention will appear as the following specific description is read in connection with the accompanying drawings which form a part of this application, and in which:—

Figure 1 is a front elevation. Fig. 2 is a top plan view. Fig. 3 is a longitudinal section taken on the line 3—3 of Fig. 1. Fig. 4 is a transverse section taken on the line 4—4 of Fig. 1. Fig. 5 is an end view of the stencil casing with the lamp casing removed. Fig. 6 is a plan view of the blank from which the panel casing is formed.

Referring more particularly to the drawings 1 and 2 represent the panel and light casings respectively which are secured together in a manner to be hereinafter described. The light casing is constructed of a single sheet of metal in the form of a frustum of a cone and has an incandescent light 3 secured therein in any suitable manner. Projecting laterally from the light casing 2 is a tube 4 which communicates at its inner end with the light casing and has secured in its outer end a red glass 5 which acts as a danger signal and is commonly called the tail light when used on automobiles.

The panel casing is constructed of a single sheet of material and comprises a front 6, back 7, top 8, bottom 9 and ends 10 and 11. The blank is constructed in the manner shown with the front arranged intermediate the top and bottom 8 and 9 and with the

bottom arranged between the front and back 6 and 7 respectively. The ends 10 and 11 being connected to and forming longitudinal extensions with the back and being provided with suitable flanges to be hereinafter described.

In forming the casing the blank is bent upon a line 12 so as to bring the top and the front at right angles to each other and is then bent upon the line 13 so as to bring the top and bottom parallel. It will be noticed that the bottom is somewhat wider than the top, both being substantially triangular in order that a stencil retaining lip 14 may be formed thereon by bending the bottom or crimping the same upon the lines 15, 16 and 17. The bottom and back are bent at right angles by bending the blank upon the line 18 which brings the free edges of the back and top together. These parts are then secured together by crimping or folding the flanges 19 and 20 together as shown in Fig. 4. The end 10 has its flanges 21 and 22 bent at right angles thereto and the end bent at right angles to the back by bending on the line 23. The flanges 22 are secured in any suitable manner to the top and bottom members while the flange 21 is secured to the front. The end 11 has its flanges 24 bent at right angles thereto and the end is then bent on the line 25 to bring the same at right angles to the back and in position for the flanges 24 to engage the top, bottom and front of the casing as will be readily understood. This end is provided with an opening to receive a conical light casing 2 which is secured therein by forming a lip 25 on the light casing adjacent its large end and spinning up the metal on the inside of the end 11.

Prior to bending the blank in shape, as just described, the front 6 is cut out as shown at 26 to produce openings and the metal intermediate the openings is cut inwardly on the lines 27 to form the ears or flaps 28, these ears or flaps are crimped or folded on the lines 29 and 30 to form blank guiding lips 31 which lips coat with the front to produce blank receiving channels 32 which register with the channel 33 formed between the front of the casing and the lip 14. The top of the casing is provided with a series of separated longitudinal slots 34 which permit the insertion of the blanks and the top has struck up therefrom suitable ears 35 which may be bent

over the blank to hold them in place. It will be noticed that when the casing is bent up into position that it is substantially triangular in top plan view so that the distance between the front and back grows smaller in the direction away from the light.

The panels may be either constructed with opaque back grounds and transparent lens or with transparent back grounds and opaque numbers. The lamp casing may be 10 interiorly silvered or otherwise treated to provide a reflecting surface and as the light is reflected therefrom it is again reflected from the back through the panels, the inclined back providing an equal reflecting surface at all points. A lamp of this character is adapted to be inserted into the back of the machine and have the front arranged 15 flush with the back, the lamp casing being entirely concealed except the red light only exposed.

What is claimed is:—

1. A sign casing formed from a single piece of material and comprising substantially rectangular front and rear walls, a top and bottom of trapezoidal formation, 20 and end walls, said front wall having a series of openings therein, said top adjacent its juncture with the front wall having a slot corresponding to each front opening with its longer dimension parallel to the

plane of the front opening and approximately equal to the width of the front opening, and bendable tongues struck up from the top and disposed at one side of the slots 25 in close proximity thereto.

2. A sign casing formed from a single piece of material and comprising substantially rectangular front and rear walls, a top and bottom of trapezoidal formation, 30 the adjacent edges of said top and rear wall being provided with bendable interlocking flanges, end walls, said front wall having a series of openings therein, said top adjacent its juncture with the front wall having a 35 slot corresponding to each front opening with its longer dimension parallel to the plane of the front opening and approximately equal to the width of the front opening, said bottom wall being bent to provide a vertical longitudinally disposed flange in alignment with the rear edges of said slots, and bendable tongues struck up from the top and disposed at one side of said slots in 40 close proximity thereto.

In testimony whereof we affix our signatures in presence of two witnesses.

PETER LEE FERGUSON.

JOSEPH W. WHEELWRIGHT.
